UNITED STATES PATENT OFFICE

WILLIAM H. STRINGFIELD, OF PHILADELPHIA, PENNSYLVANIA

DEHYDRATOR FOR PRESERVATION OF HUMAN BODIES AFTER DECEASE

Application filed July 7, 1930. Serial No. 466,058.

The main object of the invention is the provision of improved means in the way of a novel self sealing dehydrator to be installed in a coffin containing a human corpse which will aid in the indefinite preservation of the cadaver.

A further object is the provision of a novel container for the reception of desiccating material with automatic means insuring a self seal against overflow of the deliquesced desiccating material, or evaporation within a coffin.

Additional objects and advantages of the means herein employed will appear more fully in the details hereinafter set forth, reference being had to the accompanying drawing, in which:

Fig. 1 is a perspective view of a coffin wherein my novel means for preservation of the body therein has been incorporated;

Fig. 2 is a transverse sectional view of the novel dehydrator as it appears when first placed in a coffin;

Fig. 3 is a view similar to Fig. 2, showing the dehydrator in self sealed position as it appears after the lapse of some time; and

Fig. 4 is a perspective view of the elements comprising my novel dehydrator in unassembled form.

For the purpose of illustrating my invention I have shown in the accompanying drawing one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

With more particular reference to the drawing, wherein similar characters of reference indicate corresponding parts in the several views of the preferred form of the invention, A designates a casket or coffin, while B indicates my novel dehydrator.

My dehydrator comprises a vessel 8 of any suitable size and shape but preferably of a configuration which may be oval shape, as il-

lustrated, having the greatest cubical capacity with the adaptability of fitting into one of the corners of the coffin containing the cadaver 10. The vessel 8 includes an enlarged body portion 9 merging with a short 55 tubular neck 12. As an important feature of my dehydrator I include a valve which comprises an insertable cradle or support 13 formed of a pair of U-shaped straps 14—15 respectively, joined or riveted together in 60 transverse relation, the ends of each of the said straps 14—15 having flanges or bent-over portion 16, which latter serve to support the cradle 13 in depending position from the neck 12 and within the interior of the vessel 8. In 65 the cradle 13 or the enclosure formed by the U-shaped straps 14—15 a float 17, which may be of any suitable configuration but preferably cylindrical, is slidably mounted. A cap 18 having a hole 19 is secured on the neck of 70

the bottle. The annular side flange 20 of the cap 18 is clampingly engaged around the exterior periphery of the neck 12 in order to form a liquid-tight seal therein for a purpose which will hereinafter appear. Within the 75 interior of the dehydrator a quantity of desiccating or deliquescing material is placed, such as calcium chloride or any other suitable hygroscopic substance 21, it being observed that as the moisture is extracted from the interior 80 of the casket containing the body the hygroscopic material 21 through its affinity for water will gradually deliquesce and rise until the float 17 is engaged, thereby causing the latter to ascend with the gradually rising 85 liquid within the interior of the vessel 8. When the top 22 of the float 17 engages the door 23 of the cap 18 the hole 19 will be closed by the float or cork 17, thereby sealing the vessel 8, an opening formed in the vessel 90 thereby preventing further ingress of air.

This will not occur until the air within the casket has been substantially dehydrated. The amount of hygroscopic material and the size of the vessel employed to contain same 95 is always predetermined before interment, being based upon actual experience in this art. After the vessel 8 has been self-sealed in the manner indicated, spilling of the deliquesced material 21 will be prevented. The 100

top of the float may be coated with paraffin or any suitable substance adapted to form a better seal between the roof 23 of the cap 18.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new, and desire to secure by Letters Patent, is:

1. A dehydrator of the kind described comprising a vessel containing desiccating material, said vessel having an opening formed therein, and valve means automatically operated for sealing said opening thereby rendering the vessel inoperative, said valve means being responsive to the deliquescence of said desiccating material, effected by the extraction of moisture from air admitted through said opening.

2. A dehydrator of the kind described comprising in combination a vessel, hygroscopic material in said vessel, an opening in the vessel, and means including a float within said vessel operable by the deliquescence of the hygroscopic material for automatically closing said opening.

3. A dehydrator of the kind described comprising a vessel having an opening, a float slidably supported within the vessel, and means including a cap mounted on the vessel and coacting with said float for closing said opening as the float rises when material in the said vessel deliquesces.

4. A dehydrator for use in coffins containing corpses comprising a vessel having a neck having an opening communicating with the interior of said vessel, a float movable in an element secured to said neck, and a cap secured to the periphery of said neck, said cap having a hole in the top thereof registering with the said opening, said float closing said hole and opening when hygroscopic material within the vessel has deliquesced sufficiently to cause the float to rise in the element to a point where the top of said float engages the top of the cap.

WILLIAM H. STRINGFIELD.
